UNITED STATES PATENT OFFICE.

ALBERT PRIES, OF ST. LOUIS, MISSOURI.

DESIGN FOR A BATH-TUB FOOT.

SPECIFICATION forming part of Design No. 22,330, dated April 4, 1893.

Application filed December 9, 1892. Serial No. 454,668. Term of patent 14 years.

To all whom it may concern:

Be it known that I, ALBERT PRIES, a citizen of the United States, residing at St. Louis, in the State of Missouri, have invented a certain new and original Design for Bath-Tub Feet; and I do hereby declare the following to be a full, clear, and exact description of the invention, such as will enable others skilled in the art to which it appertains to make and use the same.

My design has relation to bath tub feet and the leading feature of my design consists in a bath tub foot, the configuration of which is that of an animal's paw surmounted by a fancifully ornamented capital of somewhat greater width than the paw.

In the accompanying drawing illustrating my design A, designates the base of the foot

made in imitation of an animal's paw and having sharp claws B, B, B. Above the portion A, is the ornamental capital C, of somewhat greater width than the paw and composed of the volute portions D, D, and the ornamental lines and figures between the same.

What I claim is—

The design for a bath tub foot herein shown and described.

In testimony whereof I affix my signature in presence of two witnesses.

ALBERT PRIES.
